UNITED STATES PATENT OFFICE

HARVEY J. MAHRER, OF KALAMAZOO, MICHIGAN, ASSIGNOR TO REMINGTON RAND, INC., OF WILMINGTON, DELAWARE

STEPPED-SHEET BINDER INDEX

Application filed October 5, 1927. Serial No. 224,147.

The main objects of this invention are:

First, to provide a binder and index for stepped sheets in which the variations in thickness of the sheet body occasioned by 5 the stepped arrangement of the sheets are eliminated.

Second, to provide an index sheet for use in binders or holders for sheets arranged in stepped overlapping relation which 10 supports the sheets so that they lie substantially flat.

Objects relating to details and economies of my invention will definitely appear from the description to follow. The invention is 15 defined in the claims.

A structure embodying the features of my invention is clearly illustrated in the accompanying drawing forming a part of this application, in which:

20 Fig. 1 is a plan view of a temporary binder structure in open position embodying the features of my invention.

Fig. 2 is a perspective view of one of the index sheets of the embodiment illustrated, 25 one of the filler elements being thrown out of normal position to better illustrate structure.

Fig. 3 is a detail longitudinal section of one of the index sheets.

Fig. 4 is a detail section on a line corresponding to line 4—4 of Fig. 1 showing one 30 of the sets of indexed sheets and its index sheet in normal superimposed position.

Referring to the drawing, the binder 1 illustrated is of the curved prong type, it being provided with a plurality of prongs 2. The indexed sheets are arranged in sets between index sheets 3, the set of indexed sheets comprising a plurality of sheets 4 arranged in stepped relation to expose an edge of each 40 sheet. Each of the sheets 4 has a plurality of holes 5 in its binding edge permitting engagement with selected prongs to bring about the stepped relation as shown in Figs. 1 and 4. This stepped relation produces a wedged or tapered effect toward the top and bottom 45 of the binder as will be readily understood and as is illustrated in Fig. 4.

To compensate for this the index sheets 3 are provided with tapering filler elements at 50 the top and bottom, each filler element com-

prising a plurality of superimposed strips as 6, 7, 8, 9 and 10 in the embodiment illustrated. These strips are secured to the sheet 3 at the binding edge of the sheet which has holes 11 to receive the binding prongs. The filler strips also have holes indicated at 12 to receive these prongs. 55

Each set of superimposed filler strips is provided with a cover 13 which is secured at 14 to the outer edge of the sheet 3 to overlie the filler strips and is provided with holes 15 adapted to receive the binding prongs. This arrangement effectively secures the filler strips without danger of their buckling or distorting the index sheet. 60

These index sheets are provided with index tabs 16. With the index sheets interposed between the sets of indexed sheets as illustrated, a sheet body of substantially uniform thickness from top to bottom is provided which not only supports the set of indexed sheets at the point at which the book is opened in position for proper inspection or manipulation, but supports the sheets so that they present a suitable writing surface where 70 it is desired to make entries thereon without removing from the binder. The binding being of uniform thickness, the sheet body can be more conveniently handled. 75

I have illustrated and described my improvements in an embodiment which I have found highly practical. I have not attempted to illustrate various modifications or adaptations which I contemplate as it is believed this disclosure will enable those skilled in the art to which this invention relates to embody or adapt the same as may be desired. 80

Having thus described my invention what I claim as new and desire to secure by Letters Patent is:

1. The combination with a temporary binder provided with a plurality of sheet-engaging prongs, a plurality of sets of indexed sheets engaged with said prongs in stepped overlapping relation, index sheets interposed between said sets of indexed sheets, said index sheets comprising a main sheet provided with an index tab, filler elements each comprising a plurality of strips of varying width arranged transversely of and in superimposed 95 100

relation at the tops and bottoms of said index sheets and secured at the binding edges thereof and perforated to receive the said prongs, and cover strips for said filler element strips secured at the outer edges of said index sheets and having holes at their free ends adapted to receive the binding prongs.

2. The combination with a binder provided with a plurality of sheet-engaging prongs, a plurality of sets of indexed sheets engaged with said prongs in stepped overlapping relation, index sheets interposed between said sets of indexed sheets, said index sheets comprising a main sheet provided with an index tab, filler elements each comprising a plurality of strips of varying width arranged transversely of and in superimposed relation at the tops and bottoms of said index sheets, and independent cover strips for said filler element strips at opposite ends of said main sheet.

3. The combination with a temporary binder provided with a plurality of sheet-engaging prongs, a set of indexed sheets engaged with said prongs in stepped overlapping relation, a filler comprising a main sheet and filler elements each comprising a plurality of strips of varying width arranged transversely of and in superimposed relation at the top and bottom of said main sheet and secured at the binding edge thereof and perforated to receive the said prongs, and cover strips for said filler element strips secured at the outer edge of said main sheet and having holes at their free ends adapted to receive the binding prongs.

4. An index sheet for use in combination with sheets arranged in stepped overlapping relation, said index sheet being provided with a plurality of filler strips of varying width disposed in superimposed relation at the top and bottom, and cover strips for said superimposed strips, the superimposed set of strips being secured at one edge of said index sheet and the cover strips at the other, their opposite ends being free.

5. An index sheet for use in combination with sheets arranged in stepped overlapping relation provided with a plurality of filler strips of varying width disposed in superimposed relation at the top and bottom, and cover strips for said superimposed strips at the top and bottom secured at one end to said index sheet.

In witness whereof I have hereunto set my hand.

HARVEY J. MAHRER.
